UNITED STATES PATENT OFFICE.

SAMUEL A. NEIDICH, OF EDGEWATER PARK, NEW JERSEY, ASSIGNOR, BY MESNE ASSIGNMENTS, TO THE AMERICAN MULTIGRAPH COMPANY, OF CLEVELAND, OHIO, A CORPORATION OF OHIO.

HOLDER FOR PRINTING-SURFACES.

1,089,149.

Specification of Letters Patent.

Patented Mar. 3, 1914.

Original application filed September 28, 1910, Serial No. 584,202. Divided and this application filed September 8, 1911. Serial No. 648,326.

To all whom it may concern:

Be it known that I, SAMUEL A. NEIDICH, of Edgewater Park, in the State of New Jersey, have invented a certain new and useful Improvement in Holders for Printing-Surfaces, whereof the following is a specification, reference being had to the accompanying drawings.

This application is a division of application Serial #584,202, filed September 28, 1910, for Letters Patent of the United States for improvement in duplicating-machines.

My invention relates to a printing machine having a removable printing form, and the object of the invention is to provide simple and effective means for readily locking the form in a machine and unlocking it therefrom.

My invention is particularly well adapted for embodiment in a rotary office printing machine and may be employed to hold a flexible type chase in such machine. Such an embodiment may be conveniently used for producing matter having the appearance of typewriting, and, in that case, it is desirable to provide the ink by means of a fabric extending across the type form, the fabric being suitably inked, as desired.

My invention includes the various novel features of construction and arrangement hereinafter more definitely specified.

A convenient embodiment of my invention is shown in the drawings hereof and comprises a rotary drum, means thereon for holding about the drum, in a segmental course, a flexible type chase carrying rows of individual type, and a rotary platen adapted to coact with such type when the drum is rotated. Locking means for the type chase are shown, which are adapted to be actuated by a partial rotation of the drum, when desired, as hereinafter more fully explained.

In the drawings:—Figure I is a fragmentary elevation of the right hand side of a duplicating machine embodying my invention. Fig. II is a vertical sectional view of the drum of said machine. Fig. III is a fragmentary plan view of the flexible chase shown in section in Fig. II. Fig. IV is a fragmentary plan view of the inking sheet, shown in section in Fig. II.

In said figures, the duplicating machine

frame 1 supports the rotary printing drum 8, having its shaft 9 with the operating handle 12 at one end journaled in bearings in said frame 1. Said drum 8 carries type 25 set in a detachable flexible chase, which as shown in Figs. II and III comprises the channel bars 26 which are maintained in 60 parallel relation by the flexible bands 27 connected with the opposite end attaching plates 28 and 29 extending transversely with respect to said bands; said bars and plates being conveniently riveted to said bands 27 65 as indicated in Fig. III. Said plates 28 and 29 have holes 30 and 31, to engage attaching means on said drum, including the pair of stationary hook studs 32 and the pair of oscillatory hook levers 34 projecting from 70 the circumference of said drum as shown in Fig. II and respectively adapted to engage in said holes 30 and 31. Said hook levers 34 are carried by the rock shaft 35, which as indicated in Figs. I and II is journaled in the opposite ends of said drum 8 and has the spring 37 encircling said shaft 35, engaging the pin 38 on said shaft and the pin 39 on said drum and tending to rock said shaft 35 to press said hook levers 34 80 in the direction of the arrow adjoining said shaft 35 in Fig. II, and thus wrap said chase tightly around the drum. Said shaft 35 has an arm 41 with a pin 42 exterior to said drum 8, by which said shaft may be 85 turned when said pin is engaged by the catch lever 43. Said lever is pivoted at 45 in the frame and has the spring 46 tending to hold it aside from the path in which said crank pin 42 is carried by the rotation of 90 the drum 8 in said frame. On the outer side of the frame plate 1, is a finger knob 47 having a shank passing through a slot in the frame plate and rigidly connected to the catch lever, whereby said lever may be 95 manually held in the path of said crank pin 42. Under these circumstances, a partial rotation of the drum by its crank 12 causes the pin 42 to catch in the notch in the end of the catch lever and be stopped thereby, 100 so that a slight further rotative movement of the drum swings the hook levers 34 to the opposite end of their range of movement. This enables a chase to be installed on the drum or unlocked therefrom, as the case 105 may be. The knob 47 is placed in the posi-

tion shown in Fig. I so that it may be conveniently depressed by the thumb of a hand grasping the crank 12, thus leaving the operator's other hand free to hold the chase.

5 Any desirable means may be employed for inking the type in the chase. For example, the drum may be provided with means to detachably hold stretched over the type 25 in stationary relation therewith the ink 10 transfer sheet of textile fabric 50 shown in Figs. II and IV having the attaching plates 51 and 52 with pairs of holes 53 and 54 at its respectively opposite ends; the pair of stationary studs 55 on said drum being 15 adapted to engage in either pair of said holes 53 of the plate 51, and, the plate 52 being engaged by the pair of leashes projecting from said drum, including the hooks 56 engaging in the holes 54 and connected 20 by the flexible metal tapes 59 to the spiral springs 60 carried in the tubes 61 which are in rigid relation with said drum 8. Said plate 51 is provided with two pairs of holes 53 so that said sheet may be held in different 25 positions to permit it to be uniformly worn out. Either said ink transfer sheet 50 or the type 25 may be reinked after each printing impression, said sheet 50 being employed to produce impressions resembling type- 30 writing.

The detachable chase above described is the subject matter of my Letters Patent of the United States 989,277 dated April 11, 1911.

35 I do not desire to limit myself to the precise details of construction and arrangement above described as it is obvious that various modifications may be made therein without departing from the essential features 40 of my invention as defined in the appended claims.

I claim:

1. The combination with a frame; of a printing couple including a rotary drum 45 journaled in said frame; means on said drum arranged to engage a flexible chase, including a pair of stationary hooks and a pair of oscillatory hooks projecting from the circumference of said drum; a shaft journaled in said drum and carrying said oscillatory hooks; a spring tending to rock said shaft and press said hooks in one direction; a crank on said hook shaft exterior to said drum; a catch lever pivoted in said frame; 55 a spring arranged to normally present said lever aside from the path of said crank; and, a handle on said catch lever extending exterior to said frame, whereby said lever may be manually set in the path of said 60 crank to rock the latter and press said hooks in the opposite direction.

2. The combination with a frame; of a printing couple including a rotary drum journaled in said frame; means on said 65 drum arranged to engage a flexible chase,

including a pair of stationary hooks and a pair of oscillatory hooks projecting from the circumference of said drum; a shaft journaled in said drum and carrying said oscillatory hooks; a spring tending to rock said shaft and press said hooks in one direction; a crank on said hook shaft exterior to said drum, and a movable stop adapted to be positioned to engage the crank when the drum is rotated.

3. A printing drum having means arranged to engage a chase, including a pair of stationary hooks and a pair of oscillatory hooks projecting from the surface of said drum; means including a crank exterior to said drum whereby said oscillatory hooks may be moved, and a movable stop adapted to be positioned to engage the crank when the drum is rotated.

4. A printing drum having means arranged to engage a chase, including a pair of stationary hooks and a pair of movable hooks projecting from the circumference of said drum, said movable hooks extending within said drum; spring means within said drum whereby said movable hooks may apply tension to the chase, and mechanism for automatically releasing said movable hooks consequent upon a partial rotation of the drum.

5. The combination of a drum, a flexible type chase adapted to seat thereon, a holding device on the drum for one end of the chase, a holding device on the drum for the other end of the chase including a spring adapted to keep the chase taut, and mechanism for moving the latter device against the action of the spring to release the chase, said mechanism including a rock shaft within the drum and a movable stop adapted to be positioned to engage an arm on the rock shaft.

6. The combination of a drum, a type chase adapted to seat thereon, a stationary device carried by the drum for holding one end of the chase, a movable hook carried by the drum for holding the other end of the chase, and means operating automatically upon a partial rotation of the drum for moving said hook to engage or release the chase.

7. The combination of a rotary drum, a type holder adapted to be mounted thereon, a hook adapted to engage the type holder and hold it on the drum, said hook extending from the drum outwardly through an opening therein, and means for operating said hook to release the typeholder, said means comprising a rock shaft within the drum carrying the hook, and mechanism for automatically rocking said shaft consequent upon the rotation of the drum.

8. The combination of a rotary drum; a type holder, a fastening for securing the holder in place on the drum, and means normally inactive but movable at will into

position for releasing the fastening consequent upon a partial rotation of the drum.

9. The combination of a rotary drum, a type chase adapted to be mounted thereon, a hook pivotally mounted within the drum and extending outside of the drum, a normally idle abutment, means for moving the same at will into the path of a member connected with the hook whereby in such case the turning of the drum on its axis moves the hook to release the type chase which may be held by it.

10. The combination of a rotary drum, a type chase adapted to be mounted thereon, a rock shaft within the drum, a hook carried by the rock shaft and adapted to engage the chase, an arm on the rock shaft, and a normally idle movable abutment adapted to engage the arm and rock the hook to releasing position by means of the rotation of the drum, and means for moving the abutment into such active position.

11. The combination of a rotary drum, a flexible type chase adapted to be mounted thereon, a stationary device carried by the drum for engaging and holding one end of the chase, a movable device carried by the drum for engaging and holding the other end of the chase, and normally idle means rendered active at will for automatically moving the movable device to unlock the chase.

12. The combination of a rotary drum, a type holder adapted to be mounted thereon, and normally idle means rendered active at will for releasing the type holder consequent upon the rotation of the drum.

13. The combination of a movable printing member, fastening means thereon, and normally idle means adapted to be moved at will into position to enable the movement of the printing member to move the fastening means into inactive position.

14. The combination of a movable member, a printing device adapted to be mounted thereon, fastening means for the printing device, and means actuated by the movement of the member when desired for moving the fastening means to releasing position.

15. The combination of a movable member, a typeholding blanket, fastening means therefor carried by the movable member, one of said fastening means being movable to lock or release the blanket, and mechanism for automatically moving such movable means when desired consequent upon the movement of the movable member.

16. The combination of a movable member, a type-holder adapted to seat thereon, so a hook adapted to lock the type-holder, a rock shaft carrying said hook, and mechanism thrown into action as desired for automatically rocking said shaft consequent upon the movement of said movable member.

17. The combination of a movable member, a printing device adapted to be carried thereby, a fastener for the printing device, a spring tending to hold the fastener in active position, and mechanism for moving the fastener to inactive position in opposition to such spring, said mechanism including a movable stop adapted to be positioned at will to stand in the path of mechanism carried by the movable member.

18. The combination of a movable member, a printing device adapted to be mounted thereon, a fastener for the printing device, a spring tending to hold the fastener active, so an abutment adapted to engage the fastener to move it to inactive position, said abutment being normally idle, and manual means for moving said abutment to active position.

19. The combination of a rotary drum, a printing device adapted to be mounted thereon, a movable fastener carried by the drum and adapted to engage the printing device, a spring tending to hold said fastener in active position, automatic mechanism for moving said fastener to releasing position in opposition to the spring, and a manual device movable at will for connecting in said automatic mechanism.

20. The combination of a rotary drum, a flexible type form, means for anchoring one end of the form to the drum, a movable fastener carried by the drum and adapted to engage the other end of the form, a spring acting on said fastener and tending to draw the form singly into place on the drum, an abutment adapted to be positioned to stand in the path of the fastener but normally out of said path, and a finger device for moving the abutment into the path of the fastener, whereby the rotation of the drum moves the fastener to release the flexible form, and a spring tending to return the abutment to idle position.

In testimony whereof, I have hereunto signed my name at Burlington, New Jersey, this sixth day of September, 1911.

SAMUEL A. NEIDICH.
